UNITED STATES PATENT OFFICE.

CALVIN S. BUGBEE, OF AURORA, ILLINOIS, ASSIGNOR TO HIMSELF AND
DENNIS F. VAN LIEW, OF SAME PLACE.

WHIP-SOCKET.

SPECIFICATION forming part of Letters Patent No. 290,207, dated December 18, 1883.

Application filed August 31, 1883. (No model.)

To all whom it may concern:

Be it known that I, CALVIN S. BUGBEE, a citizen of the United States, residing in Aurora, in the county of Kane and State of Illinois, have invented a new and useful Improvement in Whip-Sockets, of which the following is a specification.

My invention relates to improvements in wood whip-sockets; and the object of the invention is to cheapen and simplify the construction of such whip-socket.

In my invention the clasp or fastener by which the socket is secured to the dash-rail is made of one solid piece, and of cast metal, such fastener being cast integral with the bands which encircle the wooden barrel of the socket at each end. The metal band at the upper end of the socket also constitutes the top of the socket, thus serving also to protect the upper end of the barrel, and to secure the rubber retaining-ring or diaphragm between it and the top of the barrel. The bands are forced upon the barrel tight, so as to secure them by simple pressure. The upper band is provided with an inwardly-projecting flange or shoulder, which shoulder is beveled or made tapering, as is also the upper edge of the wooden barrel, so that the rubber ring or diaphragm will be grasped or pressed between these sharp-edged shoulders and securely held.

In the accompanying drawings, which form a part of this specification, and in which similar letters of reference indicate like parts, Figure 1 is a side elevation of a device embodying my invention. Fig. 2 is a central longitudinal section. Fig. 3 is an end or plan view of the metal top, and Fig. 4 is an enlarged sectional detail, showing the method of securing the rubber ring or diaphragm in place.

In said drawings, A represents the barrel of the socket, which is made of wood. B is the metal top, and C the metal band at the lower end of the barrel. D is the rubber ring or diaphragm, which serves as a spring to retain the whip in the socket. The barrel A has a sharp or tapering interior edge, a, at its top; and the metal top B is provided with an opposing interiorly-projecting sharp-edged flange, b, between which flange b and the edge a of the barrel the rubber ring D is grasped

and compressed. The opposing sharp edges a and b indent themselves into the rubber when the top B is forced upon the barrel A, thus forming a groove in the rubber ring D, and securely holding it in place. The clasp or fastener consisting of the jaws E E', conforming in shape to the dash-rail, are cast integral with the top B or band C, and are made of malleable iron or like material, so that the opposing jaws of the clasp may be sprung or slipped over the dash-rail, and then brought together by the set-screw e, which is threaded in the jaw E. The end of the barrel A, upon which the top B is forced, is made slightly tapering, so that the top B will fit tightly when forced thereon.

By making the fastener of cast metal, and integral with the bands B or C, and securing said bands on the wooden barrel by the pressure produced by simply driving them on, it will be seen that my whip-socket may be made at very small cost. The band B also serves as a top to protect the upper end of the barrel, as the internal flange, b, projects over the end of the barrel, so that the barrel has a metallic top, and thus performs the threefold office of, first, a metal band to clasp the wood socket; second, as an effectual means to secure the rubber ring, and, third, as a means to effectually fasten the socket to the dash-rail in the cheapest manner.

What I claim is—

1. The combination, in a whip-socket, of the barrel A, cast-metal band C, provided with fastener-jaws E E', cast integral therewith, metal top B, provided with fastener-jaws E E', cast integral therewith, and having interior shoulder, b, projecting over the end of the barrel A, and rubber diaphragm D, secured between said barrel A and top B, substantially as specified.

2. A whip-socket band and fastener having jaws E E', all cast in one piece, substantially as specified.

3. The combination of the top B, having interior projecting shoulder, b, and fastener E E', all cast in one piece, substantially as specified.

4. In a whip-socket, the combination, with a wood barrel, A, having beveled interior

edge, *a*, of the top *B*, having opposing tapering interior shoulders, *b*, and the rubber ring *D*, clasped between said sharp edge *a* and shoulder *b*, so as to indent the rubber ring and firmly hold it in place, substantially as specified.

5. The combination of the barrel *A*, with top *B*, provided with interior shoulder, *b*, fastener-jaws *E E'*, cast integral with said top *B*, and

provided with set-screw *c* and rubber ring *D*, secured between said top and barrel, substantially as specified.

CALVIN S. BUGBEE.
